UNITED STATES PATENT OFFICE.

LAURENCE G. STEWART, OF ST. LOUIS, MISSOURI.

DESIGN FOR A RING.

Application filed June 22, 1927. Serial No. 22,521. Term of patent 14 years.

To all whom it may concern:

Be it known that I, LAURENCE G. STEWART, a citizen of the United States, residing at 601 Washington Avenue, in the city of St. Louis, in the State of Missouri, have invented a new, original, and ornamental Design for Rings, of which the following is a specification, reference being had to the ac-

companying drawing, forming part thereof.

The figures are (1) an end elevation of a ring and (2) a side elevation of a ring, showing my new design.

I claim:

The ornamental design for a ring, as shown.

LAURENCE G. STEWART.
